UNITED STATES PATENT OFFICE.

JOHN F. ALLEN, OF BROOKLYN, NEW YORK.

AIR-COMPRESSOR.

SPECIFICATION forming part of Letters Patent No. 299,314, dated May 27, 1884.

Application filed April 16, 1883. (No model.)

To all whom it may concern:

Be it known that I, JOHN F. ALLEN, of Brooklyn, in the State of New York, have invented a new and useful Improvement in Air-5 Compressors, of which the following is a specification.

The nature of my invention consists, first, in the arrangement of the air-compressing cylinder, and the steam-cylinder operating the 10 same, with the intermediate frame by attaching the same to the end of said framing and allowing said cylinders to overhang the frame; second, in the manner of connecting the pistons of the air-compressing cylinder and of 15 the steam-cylinder with each other by means of rods passing above and below the crank-shaft, in connection with suitable guiding-blocks, to one of which the connecting-rod is attached.

20 In the accompanying drawings, Figure I represents a longitudinal section of an air-compressor embodying my invention. Fig. II is a vertical cross-section near the center of shaft. Fig. III shows a horizontal view of the pistons, 25 reciprocating blocks, and crank-shaft, and their connections, partly in section.

Similar letters represent similar parts.

A is the framing, with suitable bearings for the crank-shaft S, and provided at each end 30 with cylinders B and C, acting as guides for the cylindrical blocks F and M.

To the end flanges, e and b, the steam-cylinder E and the air-compressing cylinder D are attached through their respective end flanges, 35 e and d. The steam-cylinder piston G is attached through its piston-rod N with the block M, and the piston H of the air-compressing cylinder D is attached through its piston-rod J with the block F. The cylindrical block F 40 acts at the same time as the cross-head, and carries the pin L, to which the connecting-rod T (represented only by a dotted line in the drawings) is attached, the other end being connected with the crank-pin S'. The blocks 45 F and M are connected together by two or four rods, R R, passing above and below the crank-shaft S, between the sides of the cranks and the bearings of the shaft. On the ends of the crank-shaft S suitable fly-wheels are attached, to assist in regulating the motion of 50

the machine. By this arrangement I obtain a direct connection between the steam-cylinder piston G and the air-compressing-cylinder piston H, to communicate the power derived from the force of the steam acting against the 55 piston G direct to the air-piston H for compressing the air, the connecting-rod T acting only to regulate the motion of said piston.

By the arrangement of attaching the cylinders to the end of the frame and allowing said 60 cylinders to overhang, the construction is much simplified, and the cylinders are allowed a free expansion endwise without any detrimental effect to each other or to the whole machine.

In large machines the block M may be dispensed with and the rods R R pass direct through suitable stuffing-boxes into the steam-cylinder, and are there connected direct to the piston G; but I prefer the employment of the block M, as thereby the weight of the same 65 added to the weight of the block F is easily increased, and the advantages derived from these heavy reciprocating parts, as fully explained in my Letters Patent No. 237,360, of February 8, 1881, are more easily obtained. 70

Instead of making the blocks F and M cylindrical, as above mentioned, the same may be made of any other shape, and guided accordingly; but I prefer to make the same cylindrical, as thereby the frame A is made 75 more simple in construction and the whole machine more solid.

I am aware that steam-engines have been constructed with the steam-cylinder attached to the end of the bed-plate and overhanging 80 the same, and do not claim this arrangement, therefore, broadly.

I am likewise aware that steam-engines have been constructed with two or four piston-rods passing on the sides of the main shaft to a 85 cross-head situated on the other side of the shaft, and with the connecting-rod attached to said cross-head and back again to the crank-shaft, and consequently do not claim this arrangement, broadly; but 90

What I claim as my invention, and desire to 95 secure by Letters Patent, is—

1. In an air-compressor having the steam-cylinder and the air-compressing cylinder placed in one line, the steam-cylinder E and 100

the air-compressing cylinder D, attached to the ends of the main frame A, and overhanging the same, substantially as described.

2. In an air-compressing machine having the steam-cylinder and the air-compressing cylinder placed in the same line, with the crank-shaft between said cylinders, the combination of the steam-cylinder piston G, its piston-rod N, the block M, rods R R, passing

above and below the crank-shaft S, the block F, piston-rod J, and air-compressing piston H, with connecting-rod T and crank-shaft S, substantially in the manner and for the purpose herein set forth.

JOHN F. ALLEN.
